UNITED STATES PATENT OFFICE.

ALEXANDER FRASER, OF NEW GLASGOW, NOVA SCOTIA, CANADA.

DESIGN FOR A PEN-PROTECTOR.

SPECIFICATION forming part of Design No. 16,491, dated January 26, 1886.

Application filed December 4, 1885. Serial No. 184,756. Term of patent 14 years.

To all whom it may concern:

Be it known that I, ALEXANDER FRASER, of New Glasgow, Nova Scotia, Canada, have invented a new and original Design for a Pen Protector, of which the following is a full, clear, and exact description.

The drawing represents a view in perspective of my newly-designed pen-protector, as seen from its upper face side.

10 The leading feature of my design consists in the general configuration of the article as seen from its upper face side, the same resembling a letter T with its head and foot portions bent so as to form a rolling figure or 15 shape in front and with its stem or body part of a reverse arc shaped outline.

A is the head or top of the protector, which portion is of slightly curved form on its face in direction of its width, and presents opposite 20 side marginal portions, "a", throughout its depth, of a rolling shape or rolled over form in front.

B is the body or shank portion of the protector, and b b its foot or lower portions, which 25 are also of a rolling shape or rolled-over form

in front, and resemble ears. The shank or body part B, which corresponds to the stem or upright portion of the T-shaped figure of the protector, is of a reverse arc shaped outline, with its greatest width in or about the 30 middle of its length.

The ornamental rolled-over portions a a of the head may be further ornamented by scallops on their inner edges, as at c, and said portions, the rolling-shaped foot portions b b, 35 and the body or shank B be additionally ornamented by star-like figures s s, as shown.

Having thus described my invention, I claim as new and desire to secure by Letters Patent—

The design for a pen-protector herein shown and described, the same resembling a letter T, having its head portions a a made to present rolling figures with scalloped inner edges s s, foot portions b b, also made to present rolling figures resembling ears, and a body 45 part, B, of a reverse arc-shaped outline.

ALEXANDER FRASER.
